UNITED STATES PATENT OFFICE

92,605

DESIGN FOR A HEATER

Bertrand B. Kahn, Cincinnati, Ohio, assignor to
The Estate Stove Company, Hamilton, Ohio, a
corporation of Ohio

Application April 7, 1934, Serial No. 51,345

Term of patent 7 years

To all whom it may concern:

Be it known that I, BERTRAND B. KAHN, a citizen of the United States of America, residing at Cincinnati, in the county of Hamilton, State of Ohio, have invented a new, original, and ornamental Design for Heaters, of which the following is the specification, reference being had to the accompanying drawing, forming a part thereof.

The figure is a perspective view of the heater showing my new design.

The design, in the embodiment illustrated com-

prises a casing supported by a pair of base members extending from front to rear on opposite sides of the heater. The opposed side portions and the horizontal top are of a color contrasting harmoniously with the central portions of the heater and with the raised top band which extends down some distance along the central upper portion of the body.

I claim:

The ornamental design for a heater substantially as shown and described.

BERTRAND B. KAHN.
